UNITED STATES PATENT OFFICE.

ROBERT A. CONNOR, OF CHICAGO, ILLINOIS, ASSIGNOR TO THORDARSON ELECTRIC MANUFACTURING CO., OF CHICAGO, ILLINOIS, A CORPORATION OF ILLINOIS.

TRANSFORMER.

1,314,305.

Specification of Letters Patent. Patented Aug. 26, 1919.

Application filed June 28, 1915. Serial No. 36,655.

To all whom it may concern:

Be it known that I, ROBERT A. CONNOR, a citizen of the United States, and a resident of Chicago, in the county of Cook and State of Illinois, have invented certain new and useful Improvements in Transformers; and I do hereby declare that the following is a full, clear, and exact description thereof, reference being had to the accompanying drawings, and to the characters of reference marked thereon, which form a part of this specification.

This invention relates to improvements in electrical transformers, and the invention consists in the arrangement and combination of elements hereinafter specifically described and more particularly pointed out in the appended claims.

Among the objects of the invention is to provide a novel means for insulating the primary and secondary windings from each other and from the magnetic circuit structure, so arranged that insulation of a maximum insulating efficiency will occupy a minimum space. The improvements in the insulation structure are more particularly adapted to that form of transformer in which the primary and secondary windings are composed of disk like units of spirally wound conductors which surround the core of the magnetic circuit, with the high tension and low tension windings subdivided or arranged in alternation on the core in parallel planes.

A further object of the invention is to provide in a structure of this general character novel means for insulating the high and low tension elements of the winding and to provide means for directing a cooling medium, such as oil in which the transformer structure may be immersed, to the windings. This latter feature of my invention is especially adapted to that type of winding shown in U. S. Letters Patent 1,259,565, Mar. 19, 1918, of Chester H. Thordarson, wherein the windings are composed of spirally wound flat or ribbon wire with the turns insulated from each other by means which expose the edge of each turn of the winding at one or both sides thereof. This feature of my invention may, however, be applied to transformer structures wherein the windings are composed of

round conductors wound in layers spirally about the axis of the windings. 55

A further object of the invention is to provide means for exerting a tension on the turns of the winding of this character so as to maintain them tightly wound and avoid the necessity of taping the windings. 60

Other objects of the invention are to improve and simplify transformer structures.

I have herein shown my improvements as applied to a so-called shell type of transformer and one in which the high and low tension windings are composed of spirally wound flat or ribbon wire. It will be understood that certain features of the invention may be adapted to the core type of transformer, and that other features of the invention are adaptable to windings differing in their specific structure from the windings herein shown. 65 70

In the drawings:—

Figure 1 is a side elevation of a transformer embodying my invention. 75

Fig. 2 is an elevation thereof in a plane at right angles to the plane of Fig. 1.

Fig. 3 is a vertical section on the line 3—3 of Fig. 1. 80

Fig. 4 is a vertical section on the line 4—4 of Fig. 2.

Figs. 5 and 6 are edge elevations of disks constituting insulating elements employed in the transformer structure. 85

Fig. 7 is a section of a modified form of insulating element.

Fig. 8 is a sectional detail of one of the terminal elements of the low tension winding. 90

Fig. 9 is a diagram of one practical mode of connecting the high and low tension windings.

As shown in the drawings, 10 designates as a whole the magnetic circuit of the transformer. It comprises a series of superposed sheet plates of thin metal and, as herein shown, it is made up of a plurality of T-shaped plates 11 and L-shaped plates 12, with the members 14 of the T-shaped 100 constituting the core, as most clearly shown in Fig. 4. In practice, the T-shaped and L-shaped plates are arranged in alternation, so that the joints occurring between one set of plates are bridged over by overlapping 105 portions of adjacent sets of plates to thereby

avoid the presence of transverse air gaps in the magnetic circuit.

The magnetic circuit structure is bound together by means of angle bars 15, 15, the webs 16, 16 of which, lie flat against the outer sides of the laminated structure and the flanges 17 of which project laterally therefrom. The said angle bars are clamped upon the laminated structure by means of tie bolts 18, 18 which extend transversely between and through the webs 16 of the angle bar frame structure. Preferably, and in order to prevent the laminated structure from shifting relatively to the frame, the said bolts lie partially within shallow notches or recesses 19 formed in the upper and lower edges of the laminate, as most clearly shown in Fig. 4.

20, 20 designate the low tension windings 20 and 21, 21 the high tension windings of the coil structure. Said windings surround the core member 14 with opposite sides thereof occupying windows 22, 22 formed between the core member and the end members 23 of the magnetic circuit structure. In the arrangement herein shown there are an equal number of high tension and low tension windings, with two of the low tension windings disposed at the sides of the windows 30 and two other low tension windings disposed centrally of the winding group, while the high tension windings are arranged in pairs between the side and central low tension windings. The particular grouping and proportions of said windings, however, may be varied.

25, 25 designate wide, flat insulating strips which are arranged between the upper and lower sides of the windows and the windings. Surrounding the core and arranged between the same and the windings is an insulating tube or sleeve 26 which extends from side to side of the windows 22. Said tube is of a cross section to correspond with the cross section of the core member 14, it being herein shown as of rectangular cross section.

The outermost low tension windings 20 are spaced from the sides of the windows 22 by means of flat disks 27 which are jointed at their upper and lower edges to the sides of the insulating strips 25. Said disks are provided at their inner edges around their central openings with centrally arranged, inwardly extending tubular flanges 28 of a cross section to fit closely on the insulating tube 26 and upon which flanges are mounted the side low tension windings. Arranged between the central and outer low tension windings 20 and the pairs of high tension windings 21 are flat insulating disks 29, shown separately in Fig. 6. Said disks 29 are provided with centrally arranged tubular flanges 30 which fit closely upon the insulating sleeve or tube 26 and upon which

flanges are mounted the high tension windings 21. The high tension windings of each pair are separated by plain, flat insulating disks 31, the inner margins of which fit between the ends of the flanges 30 of the disks 29. The low tension windings of the central pair are likewise separated by a similar flat, plain insulating disk 32, the inner plain margin of which fits closely upon the core insulating tube 26.

The central tubular flanges 28 and 30 of the disks 27 and 29, respectively, are each made of a length to extend endwise of the core to the adjacent separating and insulating disks, so that thereby there is provided between the outer low tension windings 20 and the magnetic circuit, and between the high and low tension windings insulating barriers of substantial length such as to increase the insulating distances between said outer low tension windings and the magnetic circuit structure, and between the windings of different potentials at the inner edges of said disks as compared to an arrangement wherein the insulating barriers 90 between windings are of a length equal only to the thickness of the disks. In the latter arrangement the barrier against leakage between the windings and between the outer low tension windings and the lateral sides 95 of the windows would be only that due to the thickness of the insulating disks. With the construction and arrangement shown and described the insulating barrier against such leakage is increased a distance due to 100 the length of the central tubular flanges of said disks. With the arrangement shown, and wherein the windings are mounted on the central tubular insulating flanges of said disks, I am enabled to provide an efficient 105 insulation between the outer coils and the magnetic circuit structure and between the high and low tension windings with an exceedingly compact disposition of the insulating elements. Inasmuch as the potential 110 difference between the central low tension windings 20 is small, the provision of central tubular insulating flanges on the separating disk 32 is not required.

In addition to the arrangement of the 115 disks to afford the requisite insulation between the elements of the coil structure, certain of the disks are so arranged as to provide between the same and adjacent windings conduits 33 to direct the circulation of 120 a cooling medium, such as oil, in which the transformer structure is designed to be immersed, past the sides of the windings and in contact with the edges of the winding turns, to thereby maintain the windings 125 properly cooled. Said conduits are open to the space surrounding the windings at the edges of the disks to afford access of the cooling medium to the conduits.

The cooling medium conduits are herein 130

shown as produced by providing the insulating disks 29 on their side faces with flat spacing projections 35, 36 which are adapted to bear against the flat faces of adjacent windings in the manner clearly shown in Figs. 1, 3 and 4. The projections 35 which are engaged with the corner portions of the windings are elongated so as to extend diagonally across the windings from the inner to the outer sides thereof, while the projections 36 are smaller and laterally separated. The arrangement of said projections is such as to provide uninterrupted passage for the cooling medium along or in contact with all parts of the faces of the coils contiguous to the said spacing projections. Said arrangement of the said projections is also such as to brace the coils against lateral distortion. The spacing projections thus described constitute an exceedingly compact method of producing conduits for directing the cooling medium along the sides of the windings. As herein shown, but one side of each winding faces a cooling medium conduit, so that but one edge of each turn of each winding is exposed to the action of the cooling medium. If desired, however, all of the disks may be provided with spacing projections to produce at each side of each winding a conduit for the passage of a cooling medium, whereby both edges of each turn of each winding may be thus subjected to the action of the cooling medium.

As shown in Figs. 5 and 6, the central tubular insulating flanges 30 of the disks 29 are made integral with the bodies of the disks. In Fig. 7 I have shown a construction in which the central tubular flange 38 is made a part separate from the disk 29. It extends through the central opening of said disk and is attached to the disk by means of a flanged portion 39 which fits flat against one face of the disk around said central opening and is glued or otherwise permanently secured thereto.

As a further and separate improvement in transformer structures wherein the windings are made up of spirally wound conductors to produce flat or disk-like units, means are provided for maintaining the windings or coil sections compactly wound without the necessity of applying taping over the side members of the coils as has heretofore been a common practice. The use of the taping to stiffen the winding structure is objectionable to the extent that it excludes access of the cooling medium to the turns of the winding. The means hereinafter shown for effecting this result comprise means for placing the terminals of each winding under tension so as to prevent the outermost turns from loosening or unwinding.

First referring to the high tension windings, it will be noted that the terminals 42 are carried upwardly from the windings and are attached to the lower ends of binding posts 43 which latter extend upwardly through openings in a terminal board 44 made of insulating material. The terminals 42 of the windings may be soldered or otherwise fixedly secured to the binding posts. Said posts are screw-threaded at their upper ends to receive nuts 45 by which to exert a tensioning strain on the said wire terminals. Through said binding posts the windings may be electrically interconnected by suitable conductors or connected to external leads, depending upon the character of the connections. Between the windings and the binding posts the terminals 42 are led over sleeves 46, 46 made of insulating material and mounted on shafts 47 that extend transversely between and are attached at their ends to the webs 17 of the transformer frame. In assembling the windings upon the core they are reversed with respect to their spiral directions of winding and adjacent terminals 42 of the windings are trained oppositely about the sleeves 46 so that when the terminals 42 are tensioned the stress exerted thereupon is in a direction to tighten the windings.

The terminals 48 of the low tension windings are in like manner trained upwardly about a sleeve 49 which is mounted on a shaft 50 which extends between the frame pieces 15 at one side of the transformer frame. In the present instance each turn of the low tension winding is made up of two or more wire ribbons in order to provide the described cross section and, at the same time, to make the turns sufficiently flexible to permit them to be readily wound. The said terminals 48 extend at their upper ends into metallic bushings 51 which extend upwardly through openings in an insulating terminal board 52. The upper ends of the said bushings are screw-threaded to receive nuts 53 by which tension strains are exerted on the winding terminals to prevent them unwinding. The winding terminals 48 are connected to the bushings by means of short metallic pins 55 which extend through registering openings in the extreme ends of the terminals and the walls of the bushings, as most clearly shown in Fig. 8. The external lead wires 56 may be connected to the bushings in any suitable manner. As shown in Fig. 8 the connection is a soldered one.

The said terminal boards 44 and 52 are seated upon the upper ends of the flanges 17 of the transformer frame, which flanges are terminated short of the top of the transformer frame, and the boards are fastened to the flanges by means of hook bolts 57, as best shown in Fig. 1.

The coil structure thus grouped may be confined or held together by means of

clamping screws 65, 65 which extend through the flanges 17 of the frame and contact at their ends against insulating blocks 66 which bear against the outermost windings 5 of the group, as best shown in Fig. 1.

As herein shown and best illustrated in Fig. 9, the low tension coils are connected in parallel to the external leads 60, 61, while the high tension coils are connected in series 10 to external leads 62, 63. It will be understood, however, that the connections may be varied, as desired.

In addition to the central flanges 28, 80 and 98, the disks may be provided around their outer margins with other flanges 78, as shown in Figs. 4, 5, 6 and 7 arranged to partially fill the spaces between the upper and lower sides of the windows and the outer turns of the winding units. These 20 flanges are omitted from Fig. 1 in order to more clearly show the arrangement of the spacers 36. If the windings be made of diameters to be farther spaced from the upper and lower sides of the windows, said 25 flanges 78 may be omitted.

I claim as my invention:

1. A transformer comprising a core, subdivided disk-like high and low tension windings thereon and thin insulating elements 30 surrounding the core between the subdivided windings to insulate the high and low tension windings from each other and formed at their inner edges with continuous laterally directed insulating means which 35 surround and extend lengthwise of the core between the latter and the windings to augment the insulating barrier between the windings at the inner edges of said insulating elements beyond that due to the thickness of said insulating elements.

2. A transformer comprising a core, side- 45 wise disposed, subdivided, disk-like high and low tension windings thereon, insulating disks surrounding the core between the windings and provided with continuous flanges which surround the core within the windings, whereby the insulating distance between adjacent windings at the inner edges of said elements is increased, and 50 means to provide conduits between certain of the disks for the passage of a circulating cooling fluid.

3. A transformer comprising a core, side- 55 wise disposed, subdivided disk-like high and low tension windings thereon and insulating disks surrounding the core between the windings provided with inner edge flanges extending lengthwise of the core, between the latter and the internal surfaces of the wind- 60 ings, whereby the insulating distance between adjacent windings is increased at the edges of said disks, certain of disks being provided with face projections to engage adjacent sides of the windings to thereby 65 space the disks from the windings and pro-

duce cooling medium circulating conduits along the flat faces of the windings.

4. A transformer comprising a core, side- 70 wise disposed, disk-like subdivided high and low tension windings thereon and insulated from the core, insulating disks between the windings, certain of which are provided with flat face projections to engage adjacent sides of the windings to thereby space the disks from the windings and produce 75 cooling medium circulating conduits along the flat sides of the windings.

5. A transformer comprising a core, side- 80 wise disposed, disk-like subdivided high and low tension windings thereon each comprising a bare edge spirally wound flat or ribbon wire, with insulating strips between the turns thereof, thin insulating disks also surrounding said core between said windings and provided with central flanges which surround the core within said windings, the side faces of said disks being provided with out- 85 standing projections which engage the flat faces of the windings to provide cooling medium conduits to direct a cooling medium 90 to the bare edges of all of the turns of the windings.

6. A shell type transformer comprising a magnetic circuit formed with windows to receive the windings and a central core, 95 grouped, sidewise disposed, disk-like subdivided high and low tension windings surrounding said core and extending through said windows, insulating disks surrounding the core between the sides of the windows 100 and the outer windings of the group and provided with tubular flanges arranged between the core and said outer windings, and insulating disks interposed between other windings of the group, certain of which are 105 provided with central flanges disposed between the core and adjacent windings.

7. A shell type transformer comprising a magnetic circuit formed with windows to receive the windings and a central core, 110 grouped, sidewise disposed, disk-like windings surrounding said core and extending through said windows, insulating members between the tops and bottoms of said windows and said windings, from which said 115 windings are spaced to constitute cooling medium conduits, and insulating disks surrounding the core between the windings, with their side faces formed to constitute cooling medium conduits at the flat sides of 120 said windings.

8. In a transformer, a series of windings composed of spirally wound conductors with the turns thereof insulated and means to tension the terminals of the windings, for 125 the purpose set forth.

9. In a transformer, a series of windings composed of spirally wound conductors, with the turns thereof insulated and means to exert a variable tension on the terminals 130

of said windings in the direction of their spiral turns to thereby maintain the windings closely wound.

10. In a transformer, a winding composed
5 of a spirally wound flat ribbon wire with
insulation between the turns thereof, and
means to maintain said winding compact,
comprising means to exert tension on the
terminal of the winding.
- 10 11. In a transformer a magnetic core, a
series of disk like windings thereon com-
posed of spirally wound conductors, a ter-
minal board through which the terminals of
said windings extend, and means associated
15 with said terminal board and said terminals
to exert a winding tension on said windings,
for the purpose set forth.
12. A transformer comprising a core,
sidewise disposed, disk-like subdivided high
20 and low tension windings thereon, and thin
insulating elements surrounding the core
between the windings and certain of which
are formed at their inner and outer edges
with right angle flanges to continuously em-
brace the inner and outer edges of the wind-
ings to increase the insulating barrier be-
tween the windings, certain of the disks
25
- being formed to provide between the same
and adjacent windings conduits for the cir-
culation of a cooling medium. 30
13. In a transformer, a flat insulating disk
to separate winding units and having a cen-
tral opening to fit around the core and pro-
vided around said opening with a right-
angle flange and on its flat face with inter-
spaced, relatively small area winding unit
sustaining and conduit forming projections. 35
14. In a transformer, an insulating disk
to separate winding units and having a cen-
tral opening to fit around the core, and pro-
vided around said opening with a right
angle flange, said disk being provided about
its periphery with a like flange, and pro-
vided on its flat face with interspaced rela-
tively small area-winding unit sustaining 40
and conduit forming projections. 45

In testimony, that I claim the foregoing
as my invention I affix my signature in the
presence of two witnesses, this 29th day of
May, A. D. 1915.

ROBERT A. CONNOR.
